COMBINATION BASKET AND PIE RACK

Harland W. Whitmore, Kenosha, Wis., assignor
to Motor Products Corporation, Detroit, Mich.,
a corporation of New York

Application February 11, 1952, Serial No. 270,929

7 Claims. (Cl. 312—213)

1

This invention relates generally to article holding containers, and refers more particularly to improvements in wire baskets of the type used, for example to support articles within a cabinet.

One use for wire baskets embodying the features of this invention is in connection with home freezers where it is advantageous to compactly arrange a wide variety of food articles, and at the same time, provide easy access to the articles. A wire basket constructed in accordance with this invention may be supported within a home freezer cabinet for sliding movement to different positions so that articles contained within the cabinet below the basket may be conveniently reached. Also the interior of the basket is divided into separate top and bottom storage spaces by a shelf or rack removably supported within the basket substantially midway between the top and bottom of the basket. In addition the top of the basket is open enabling insertion of the shelf into and removal of the shelf from the basket. Also one side of the basket is open throughout its area permitting easy access to both of the storage spaces in the basket while the latter is supported within the cabinet.

It is a further object of this invention to provide a closure for the open side of the basket in the form of a wall of open wire mesh construction having the top edge hingedly supported on the basket for outward swinging movement, and having means engageable with latch means on the basket to hold the closure against accidental movement from its closed position.

The foregoing as well as other objects will be made more apparent as this description proceeds, especially when considered in connection with the accompanying drawings, wherein:

Figure 1 is a semidiagrammatic top plan view of a home freezer cabinet showing my improved basket in assembled relation therewith;

Figure 2 is a plan view of the basket;

Figure 3 is a side elevational view of the basket shown in Figure 2;

Figure 4 is an end elevational view of the basket shown in Figure 2;

Figure 5 is a top plan view of a removable shelf or rack for the basket;

Figure 6 is a sectional view taken on the line 6—6 of Figure 5;

Figure 7 is a fragmentary perspective view of the latch means associated with the basket;

Figure 8 is a fragmentary sectional view of the basket showing the shelf or rack in place, and

Figure 9 is a fragmentary perspective view of one corner of the basket.

2

Upon reference to Figure 1 of the drawings, it will be noted that the numeral 10 designates a cabinet of the type commonly used for home freezers and the numeral 11 indicates a storage container in the form of a wire basket. The top of the cabinet is open for substantially the full area of the cabinet to provide access to the interior of the cabinet and the basket 11 is supported within the cabinet for sliding movement in the direction of length of the cabinet. For this purpose a pair of guide rails 12 are respectively secured to the inner surfaces of opposite side walls of the cabinet and parts of the basket at opposite sides thereof seat on the rails. The rails 12 are usually located near the open top of the cabinet, and the depth of the basket 11 is preferably considerably less than the depth of the cabinet so that a storage area of generous proportions is provided below the basket. The arrangement is such that articles occupying the storage space directly below the basket 11 may be conveniently reached by merely sliding the basket 11 along the rails 12.

The basket 11 has one side 13 completely open and comprises a bottom wall 14, a rectangular bordering frame 15 at the top, a side wall 16 opposite the open side 13, and connecting or end walls 17. The open side 13 is normally closed by a wall 16' having its top edge hingedly connected to the frame 15 for outward swinging movement. All of the walls of the basket are of a wire open mesh construction in order to enable free circulation of air through the basket and this is especially important in instances where the basket is used for the purpose of storing articles within a refrigerator or home freezer cabinet.

Each of the walls of the basket are formed of a number of strands of wire spaced laterally from each other to provide openings of substantial area and the wire strands are welded or otherwise permanently connected to form a strong, durable structure. Also the bottom wall 14, side wall 16 and end walls 17 are connected together and to the frame 15 in a manner to provide an integral structure possessing substantial stability.

The frame 15 at the top of the basket has a side bar 19 which extends along the side wall 16 of the basket and is welded or otherwise secured to the wire strands forming this side wall. The opposite ends of the side frame bar 19 are respectively integrally connected to end bars 20 which extend along the end walls 17, and are welded or otherwise secured to the wire strands forming the end walls 17. As shown in Figures 2, 8 and 9 of the drawings the end frame bars

20 are spaced laterally outwardly from the adjacent end walls 17 of the basket 11 and the upper ends of the wires forming the end walls 17 are bent laterally outwardly to enable welding or joining the same to the end frame bars 20. The construction is such that the end frame bars 20 form seats at the top of the basket for engagement with the guide rails 12 in the cabinet 10.

The frame 15 also has a side bar 21 which extends along the open side 13 of the basket 11 at the top of the latter, and is welded or otherwise secured to the upper ends of the wire strands 22 forming the closure or hinged wall 16'. Suitable enlargements 23 are provided on the extremities of the bar 21 at the outer sides of the end bars 20, and projections 24 are formed on the bar 21 at the inner sides of the end bars 20 to hold the closure or wall 16' in proper relationship to the open side of the basket. Also as shown in Figure 4 of the drawings the ends of the frame bars 20 engaged by the hinge bar 21 are offset upwardly with respect to the remainder of the bars 20 in order to provide a clearance between the hinge bar 21 and the rails 12 when the basket 11 is supported within the cabinet.

It will be noted from the foregoing that when the basket 11 is supported in the cabinet 10 on the rails 12, the open side 13 and hinged closure or wall 16' assume positions enabling the wall 16' to be swung to its open position while the basket is supported on the rails 12. Thus the basket 11 may be loaded and unloaded without removing the same from the cabinet 10. It will also be noted that the hinged connection between the wall or closure 16' and basket enables swinging the closure to a position where it overlies the top of the basket, and is thereby held in its open position while articles are inserted into or removed from the basket.

It will further be noted from Figure 4 of the drawing that the bottom wall 14 of the basket terminates short of the hinged closure or wall 16', and that the resulting space is closed by an extension 25 projecting laterally inwardly from the bottom edge of the wall 16'. The extension 25 forms a continuation of the bottom wall 14 of the basket 11 in the closed position of the wall 16', and is formed by turning the bottom portions of the wires 22 laterally inwardly as at 26. As shown in Figure 2, the extremities of the turned portions 26 of the wires 22 are connected by a cross wire 27 which abuts the adjacent side of the bottom wall 14 in the closed position of the wall 16'. Thus the access opening actually extends for a short distance along the bottom of the basket and unloading as well as loading of the basket is facilitated.

The wall 16' is held in its closed position by a U-shaped latch member 28 positioned midway between the end walls 17 and having the leg portions 29 welded or otherwise secured to laterally spaced wires forming a part of the bottom wall 14 of the basket. The base portion 30 of the U-shaped latch member 28 is spaced laterally outwardly from the cross wire 27 and the leg portions 29 adjacent the base 30 are bent to form spring clips 31. The clips 31 are fashioned to frictionally engage the wire 27 as the closure or hinged wall 16' is swung to its closed position, and are shaped to effectively latch the wall 16' in its closed position. Also the design of the clips

31 is such that the clips are released from the cross wire 27 in response to a force exerted in an outward direction on the bottom of the wall 16'.

5 The interior of the basket is divided into top and bottom storage spaces by a wire rack or shelf 32 having a rectangular bordering frame 33. The rack or shelf 32 is insertable into and removable from the basket 11 through the top frame 15 of the basket, and is removably supported in the basket on lengths of wire 35 which extend along the end walls 17 midway between the top and bottom walls of the basket. As shown in Figures 5 and 6 of the drawings, the shelf 32 has looped cross wires 36 welded at the opposite ends to the adjacent side bars 37 of the frame 33, and has longitudinally extending laterally spaced wires 38 welded to the cross wires 36. The opposite ends of the wires 38 extend beyond the end bars 39 of the frame 33, and are fashioned to provide downwardly directed hooks 40. The hooks 40 are positioned to respectively engage the wires 35 extending along the end walls 17 of the basket and coact with the latter wires 35 to removably support the shelf 32 on the basket. The shelf frame 33 is smaller than the frame 15 and hence may be readily inserted into and removed from the basket 11 through the top of the latter.

When the rack or shelf 32 is in assembled relationship with the basket, the storage spaces provided in the basket above and below the shelf are accessible through the open side 13 of the basket in the open position of the closure 16'. The use of the rack or shelf 32 is especially advantageous in instances where it is desired to store such food articles as cakes and pies. In this connection it will be noted that food articles such as cakes and pies may be stored within the basket without danger of bumping or otherwise disturbing the articles when loading or unloading the cabinet. Also the food articles stored within the basket may be conveniently inserted into or removed from either or both the storage spaces through the open side of the basket without removing the latter from the cabinet.

What I claim as my invention is:

1. A container for supporting articles in a cabinet, comprising a wire basket open at one side and having a bottom wall terminating short of the open side thereof, a side wall opposite the open side and connecting walls at opposite ends of the side wall, a closure for the open side of the basket in the form of a wall spaced laterally outwardly from the open side of the basket and hingedly connected at its top edge to the basket for upward swinging movement, and a wire extension projecting laterally inwardly from the bottom edge of the closure and forming a continuation of the bottom wall in the closed position of the closure.

2. The container defined in claim 1 having a spring catch for releasably latching the closure in its closed position.

3. A container for supporting articles in a cabinet, comprising an open mesh wire basket having one side open and having a bottom wall, a side wall opposite the open side, and end walls, supporting bars respectively extending along the end walls at the top of the basket and projecting beyond the open side of the basket, and bars spaced laterally outwardly from and respectively connected to the end walls providing supports for slidably engaging laterally spaced guides, a closure for the open side of the basket and having a side wall spaced laterally outwardly from the open side of said basket, said closure having

5

a bottom wall extending laterally inwardly from the side wall thereof and forming a continuation of the bottom wall of the basket in the closed position of said closure, and means hingedly connecting the top of the side closure wall to the projecting ends of the supporting bars of the frame permitting upward swinging movement of the closure to a position in overlying relationship to the top of the basket.

4. The container defined in claim 3 wherein the closure is of open wire mesh construction and has a bar at the inner side of the bottom wall arranged to abut the adjacent side of the bottom wall of said basket.

5. The container defined in claim 4 comprising a spring catch supported by one of said bottom walls for engagement with the other to hold the closure in its closed position.

6. A container for supporting articles in a cabinet, comprising an open mesh wire basket open at the top and at one side, said basket having end walls, a side wall opposite the open side and a bottom wall terminating short of the open side of the basket, a wire mesh closure for the open side of the basket and having a wall spaced laterally outwardly from the open side of the basket, said closure wall having an extension projecting

6

laterally inwardly from the bottom edge thereof and forming a continuation of the bottom wall of the basket, means hingedly connecting the top of the closure wall to the end walls of the basket permitting upward swinging movement of the closure to its open position, a shelf insertable into and removable from the basket through the open top of the basket in the closed position of the closure, and means removably supporting said shelf on the end walls of the basket.

7. The structure defined in claim 6 wherein the shelf supporting means comprises lengths of wire secured to the end walls between the top and bottom of the basket, and projections on said shelf seated on the lengths of wire.
